US0D1113473S

(12) **United States Design Patent** (10) **Patent No.:** **US D1,113,473 S**
(45) **Date of Patent:** **** Feb. 17, 2026**

(54) **HAND-HELD METAL DETECTOR**

(71) Applicant: **Garrett Electronics, Inc.**, Garland, TX (US)

(72) Inventors: **Stephen M. Novakovich, Jr.**, Dallas, TX (US); **Robert J. Podhrasky**, Dallas, TX (US); **Tunga Tuzlaci**, Plano, TX (US); **Brent C. Weaver**, Heath, TX (US)

(73) Assignee: **Garrett Electronics, Inc.**, Garland, TX (US)

(**) Term: **15 Years**

(21) Appl. No.: **29/969,631**

(22) Filed: **Oct. 23, 2024**

(51) **LOC (15) Cl.** **10-04**
(52) **U.S. Cl.** **D10/47**

(57) **CLAIM**

The ornamental design for a hand-held metal detector, as shown and described.

DESCRIPTION

FIG. 1 is a top side view of a hand-held metal detector according to the design;

FIG. 2 is a bottom side view thereof;

FIG. 3 is a top end view thereof;

FIG. 4 is a bottom end view thereof;

FIG. 5 is left side view thereof;

FIG. 6 is a right side view thereof;

FIG. 7 is a top side perspective view thereof;

FIG. 8 is a bottom side perspective view thereof;

FIG. 9 is a top side perspective view thereof; and,

FIG. 10 is a bottom side perspective view thereof.

The broken lines shown throughout these figures depict portions of the hand-held metal detector that form no part of the claimed design.
